ANGUS F. BARRY, OF KANSAS CITY, MISSOURI; MARY ELLEN BARRY EXECUTRIX OF
SAID ANGUS FERRY BARRY, DECEASED.

PROCESS OF TREATING AND PRESERVING WOOD.

1,197,997.

Specification of Letters Patent. Patented Sept. 12, 1916.

Application filed April 19, 1915. Serial No. 22,444.

To all whom it may concern:

Be it known that I, ANGUS F. BARRY, a citizen of the United States of America, residing at Kansas City, in the county of Jackson and State of Missouri, have invented certain new and useful Improvements in the Processes of Treating and Preserving Wood, of which the following is a specification.

The invention relates particularly to the processes of wood preservation in which the sap is removed from the sap channels by a preliminary sweating process, to which the wood is subjected in a heated vacuum, previous to the application of the preservative, as described in the specification forming a part of the Letters Patent of the United States granted to me under date of October 24, 1911, and numbered 1006713.

The object of the present invention is to treat various kinds of wood, which have previously resisted the penetration of the preservative, such as non-porous woods, fir being one well known species, and also for the treatment of such wood as has been case-hardened from exposure to the weather.

The further object of the invention is to subject the wood to be treated while in a heated vacuum to cause sweating of the wood, and without breaking the vacuum, equalize the expansion of the rings of the non-porous wood with the other portions of the wood and also of the case-hardened portion of the wood, so as to prevent checking or splitting of the wood, from unequal expansion, and effect a complete penetration of the preservative.

In the accompanying drawings: Figure 1 is a longitudinal, sectional view of a horizontal cylinder or retort, employed in the creosoting of wood, showing the door in an open position, and the wood to be treated upon a car, which is mounted on the track rails within the cylinder; and Fig. 2 is a transverse, vertical, sectional view of the cylinder or retort, taken upon the line $x-x$, in Fig. 1, and showing one of the steam-condensing chambers in section, the door of the cylinder being closed.

7 indicates the retort, one end being closed, 50 the other end having a door opening 6, adapted to be hermetically closed by the door 10, which door is secured by bolts 11.

8 indicates the track rails in the bottom of the cylinder, and 5 the flat bottom car upon said rails, upon which the wood to be treated is stacked.

12 indicates a pipe coil in the top of the cylinder for the heating medium, and 13 and 14 are respective ends of said coil, extending through the top of the retort. 13^x, 60 14^x, are valves in said ends of the coil, the coil being supplied with steam from a suitable source of steam supply.

15 indicates the gage for indicating the temperature within the retort, and 16 the pipe connecting the gage with the retort 7.

16^x indicates the temperature bulb.

17 represents a gage for indicating the degree of vacuum within the retort, and 18 the pipe connecting said gage with the retort.

18^x is a valve in pipe 18.

19 represents a gage for indicating the oil pressure within the tank, and 20 the pipe leading from the gage to the retort or cylinder.

20^x is the valve in pipe 20.

23 is the exhaust pump for exhausting the air from the cylinder retort 7, and 22 the pipe leading from the retort to the pump.

21 is a valve in the pipe 22, for opening up the retort to the action of the exhaust pump 23.

26 is a spherical steam-condensing case 85 having the chamber 25, and 24 is a pipe for steam leading within the receiver 26, and 27 is the cut-off valve in pipe 24.

28 is a pipe for the supply of air, leading within the receiver 26 and in a position 90 directly opposite the discharging end of the steam pipe 24.

29 is a valve in the pipe 28.

31 is a dome within the lower section of chamber 25, of receiver 26, the dome having 95 a deflecting convex surface 30.

32 indicates the pipes for supplying the preserving oil or creosote to the retort, and 33 are the cut-off valves in pipes 32.

34 indicates a thermometer for indicating 100 the temperature within the retort 7, around the heating coil 12 and 34^x the temperature bulb.

36 represents a compressed air storage

tank, and 35 a pipe connected with said tank and with the retort 7, and at the central point of the closed end 9 of said retort.

35^x indicates the valve for admitting the compressed air from tank 36 to the retort.

37 represents a gage on the tank 36, for indicating the air pressure in tank 36.

38 indicates a check valve in the pipe 35.

40 indicates the discharge pipe for the air in the bottom and forward end portions of the retort or cylinder 7, and 39 the valve in said pipe.

The wood which is subjected to treatment under my process, such as may be instanced 15 lumber, for railroad uses, is stacked longitudinally upon the flat bottom car 5, and the car with its load is moved within the door opening 6, of the retort or cylinder 7, on the track rails 8, which retort is adapted to

20 receive the lumber in large quantities for treatment. The hinged door 10, of the retort, is then closed, and secured by the bolts 11, hermetically sealing the door opening 6. In this process the wood is preferably sub-

25 jected to the sweating process described in the Letters Patent granted to me and before mentioned, in which the heat from the steam coil 12, located in the upper portion of the retort, produces a temperature, approxi-

30 mately 115° Fahrenheit, or the boiling point of water in vacuum, the supply of steam being regulated by the valves 13^x, 14^x, which are opened to the proper extent, the temper-

35 ature around the coil being indicated by the thermometer 34. When the air in the retort or cylinder 7 becomes heated at the boiling point of water in vacuum indicated by the temperature gage 15, the valves 13^x and 14^x are closed, and valve 21, in pipe 22,

40 leading from the bottom of the retort, is partially opened, and suction is produced upon the heated air within the retort, gradually forming a vacuum within said retort sufficient to distribute the heated air

45 throughout the retort and downwardly through the wood, the action of the rarefied, heated air producing a sweating of the wood, and rapid release of the sap from the cellular portions of the wood, leaving the cellular

50 portions fully open, the sap falling to the bottom of the cylinder and being removed through pipe 22, by the suction pump 23, the opening of the exhaust valve being gradually increased during the action of the

55 pump, the accumulation of liquids of condensation being removed thereby, and re-absorption by the wood prevented. In this treatment the glutinous scale formed on the walls of the cellular portions dissolves and

60 passes out in a soluble condition with the sap, through pipe 22, by the action of the pump 23, while the volume of heated air is drawn downwardly from the top of the retort by a slow and progressively increasing

65 vacuum. The determination of the dry-

ness of the wood is indicated by the decreased amount of condensation obtained.

The absence of moisture in the wood being treated being perceived in the meager discharges of the sap, the rings of the non-

70 porous portions of the wood, and the case-harden-

75 hardened portions of the wood are softened and made equally receptive for the oil penetration.

The succeeding step in the process is to produce in the heated, dry atmosphere

75 within the retort, sufficient vapor to soften the rings of the case-hardened parts of the

80 wood without breaking the vacuum within the retort, so essential to preserve, while the action of the vapor is taking place upon said

85 rings or case-hardened parts. The temper-

85 ature within the cylinder being now at the proper degree, as indicated by the temper-

90 ature gage 15, and the vacuum by the vacuum

95 gage 19, the valve 20^x, in the pipe 20, is

95 opened to show the amount of vacuum, which is constantly maintained at the boil-

100 ing point of water, in approximately 26 de-

105 grees of vacuum, during the next step, which is as follows: Steam from a suitable

110 source and, under pressure is conducted through the steam supply pipe 24, to the condensing chamber 25, in the chamber 26,

115 upon the opening of the valve 27, and air is admitted to the chamber 25 through the

120 pipe 28, upon the opening of the valve 29, the steam and air entering in the line of the

125 diameter of the receiver 25 and from oppo-

site directions, the air coming into direct

130 contact with the steam and condensing the

135 steam into moisture above the convex sur-

140 face 30 of the dome 31, in the lower portion of the case 24. The moisture from con-

145 densation passes through said opening 30^x,

150 in the dome 30, into the retort 7, without

155 breaking the vacuum in the retort, the same

160 vacuum being produced within the case 24, from the action of the vacuum pump 23. The temperature of the case 24 during the

165 condensation of the steam is found to be

170 cold. The moisture from condensation of the steam, upon entering the retort 7 passes

175 over the heated coil 12, within the retort, penetrates the cellular and case-hardened

180 portions and the rings of the non-porous wood equally, the expansion of said parts

porous wood, which is found by frequent tests, the valve 21 in the pipe 22, and the valves 27 and 29 in the respective pipes 24 and 28, are closed. The preserving oil, such as creosote, is then admitted to the retort through the pipes 32, upon opening of the valve 33. The temperature of the oil is from 90° to 200° Fahrenheit, and enters the retort under pressure, destroying the 10 vacuum. The heated oil passes over the steam heated coil 12, and through the wood charge, and a subsequent pressure of 140 or more pounds is applied to the oil, which is indicated by the oil pressure gage 17.

15 When the penetration of the wood and its rings, or the case-hardened portions is completed, the valves 33, in pipes 32, are closed. Compressed air, which is cooled by expansion to a temperature of 30° to 40° Fahrenheit, is then admitted to the retort through the pipe 35, containing check valve 38, and leading from the compressed air storage tank 36, through said pipe, and centrally to the end plate 9, of the retort, at approximately 20 80 to 100 pounds, as indicated by the gage 37. The outlet valve in the pipe 40 is then opened to a small extent, to reduce the pressure now on the oil to 80 or 100 pounds pressure, until the pressure on the oil and 25 the air obtains equal pressure, and these pressures maintained for the necessary period of oil penetration. The gradual discharge of the oil from the retort, and the action of the cold, compressed air under 30 expansion, forces the body of the oil through pipe 40, in a restricted quantity, while holding the air pressure as indicated by gage 37, on tank 36, at 80 to 100 pounds upon the hot preserving oil. As the volume of the 35 preserving oil decreases, the volume of cold, compressed air is increased, and passes through the wood charge, contracting the wood, so that the fiber structure is not injured, and the cellular portions and the rings 40 of the non-porous wood receive equal penetration. Upon the full opening of the valve 39, in pipe 40, the excess of oil is blown out of the retort by the expanded air, the cold air drying the wood, while the wood is 45 within the retort. The valve 39 is then closed, the door 10 to the retort opened, and the preserved lumber removed therefrom.

50 The value of the process is understood by those skilled in the art, and has been practically demonstrated by me, in a section of the country in which the species of timber known as Douglass fir is indigenous. The rings of the non-porous species of wood, which are seasoned and contain the hardened gum, under all previously known processes split from the cellular portions, and the only successful method has been under my invention, to permit the wood, while in a heated vacuum, to absorb the amount of 55 vapor required to the rings, the cellular portions, equally, without breaking the vacuum, hence no splitting or checking occurs. To expose the case-hardened wood to steam, or even the surrounding moisture from the sap, will not affect the case-hardened part of 60 wood, except to separate one part from the other. In my process the expansion and contraction of one part will not check the case-hardened part of the wood, because no vulcanizing methods are used, nor could be 65 employed in a heated, dry vacuum, without breaking the vacuum, and hence, I have discovered and put into successful operation the only known process for the treatment of 70 non-porous and case-hardened wood. 75

Not only fir, but hemlock has been successfully treated under my process, the result being proven that the tensile strength of the wood is increased, as well as its longevity.

Having fully described my invention, what I now claim as new and desire to secure by Letters Patent is:

1. The herein described process of treating case-hardened and non-porous wood 80 for the penetration of a preservative without checking of the wood, which consists in subjecting the wood to a heated vacuum and supplying a vapor below the boiling point of water for the absorption of the vapor 85 equally by the cellular and case-hardened portions or rings of the wood without breaking the vacuum.

2. The herein described process of treating case-hardened and non-porous wood for 100 the penetration of a preservative without checking of the wood, which consists in introducing within a retort within which a heated vacuum is maintained, of a determinate amount of moisture converted by 105 the heat within the retort into a vapor which acts upon the case-hardened portions of the wood and without breaking the vacuum.

3. The herein described process of treating non-porous and case-hardened wood for 110 the penetration of a preservative, which consists in heating the air above the wood being treated within a retort, applying suction to create a vacuum, and thereby drawing down the rarefied heated air through the 115 wood charge to cause sweating of the wood, and then drawing a determinate amount of moisture which is converted into vapor by the heat within the retort through the wood charge without breaking the vacuum. 120

4. The herein described process of treating non-porous and case-hardened wood for the penetration of a preservative, which consists in heating the air above the wood being treated within a retort, applying suction to create a vacuum, and thereby drawing down the rarefied heated air through the 125 wood charge to cause sweating of the wood, and then drawing a determinate amount of moisture converted into vapor by the heat 130

4
within the retort through the wood charge without breaking the vacuum, then subjecting the wood to hot preserving oil, thereby destroying the vacuum.

5 5. The herein described process of treating and preventing checking of case-hardened and non-porous wood, consisting in heating the air above the wood being treated in a retort, and then applying suction to
10 create a vacuum within the retort, condensing steam with the aid of air to form moisture, drawing sufficient moisture converted into vapor by the heat within the retort

through the wood charge without breaking the vacuum, subjecting the wood to hot preserving oil under pressure and destroying the vacuum, then admitting compressed air under expansion and at a low temperature to one end of the retort to displace the oil through the wood charge, then decreasing the pressure on the oil by a gradual escape of the oil from the retort.
